UNITED STATES PATENT OFFICE.

WARD S. IRELAND, OF OWENSBORO, KENTUCKY.

STENOGRAPHIC TYPE-WRITING MACHINE.

1,098,115.

Specification of Letters Patent. Patented May 26, 1914.

Application filed March 11, 1913. Serial No. 753,632.

To all whom it may concern:

Be it known that I, WARD S. IRELAND, a resident of Owensboro, in the county of Daviess and State of Kentucky, have invented certain new and useful Improvements in Stenographic Type-Writing Machines; and I do hereby declare the following to be a full, clear, and exact description of the invention, such as will enable others skilled in the art to which it appertains to make and use the same.

This invention relates to improvements in type-writing machines and particularly to stenographic writing machines, the object 15 of the invention being to provide means whereby the various operating mechanisms, including the key and type lever mechanism, the paper-feeding mechanism and the inking ribbon mechanism, may have their 20 strokes adjusted simultaneously and to so construct and arrange such adjusting means that it shall be readily accessible, easy to manipulate, and accurate in operation.

With this object in view the invention 25 consists in certain novel features of construction and combination of parts as hereinafter set forth and pointed out in the claims.

In the accompanying drawings; Figure 30 1 is a longitudinal sectional view of a stenographic writing machine embodying my improvements; Fig. 2 is a rear elevation showing the adjusting device, and Fig. 3 is an enlarged side elevation, partly in section 35 showing the adjusting device and its application.

1 represents the frame of a type-writing machine provided at its rear end with a door 2 on which a bracket 3 is located and 40 adapted to support a supply roll 4 of paper. A platen 5 is located over the upper portion of the frame 1 and in the lower portion of said frame a key lever bearing 6 is secured. A plurality of key levers 7 (each provided 45 at its inner or rear end with a suitable key or button 8) have pivotal bearings in the mounting 6 and each of said key levers is provided with an upwardly projecting arm 9 having a loose pivotal connection at its 50 upper end with the lower arm of a type lever 10, the upper arm of said type lever being provided with a type normally disposed in front of the platen. Thus it is apparent that when a key is depressed, motion 55 will be imparted through the key lever

to the type lever and cause the type on the upper end of the latter to move toward the platen, it being of course understood that an inking ribbon and a paper strip will be disposed between said type and platen as will 60 be more fully hereinafter set forth.

The paper strip will be fed from the roll 4 past the platen and will be guided in its movements by guides such as illustrated at 11, 12, and 13, the paper passing from the 65 guide 13 rearwardly through a paper-feed mechanism 14. This paper-feed mechanism includes levers 15 to the lower ends of which links 16 are pivotally connected. These links project forwardly and are connected at their forward ends to rearwardly projecting arms 17. The arms 17 project rearwardly from the lower ends of links 18 pivotally suspended from a fixed part of the mechanism. The suspended links 18 serve 70 to support a universal bar 19, the ends of which latter are secured to said links and the said universal bar is disposed in front of the type levers in proximity to the pivotal connection of the latter with the key lever 75 arms 9.

Inking ribbon spools, such as illustrated at 20, are provided and the inking ribbon passes from one of these spools to the other and between the type and the paper strip, 80 as will be readily understood. Ratchet mechanism 21 is provided for actuating the ribbon spools and is connected with the latter through the medium of suitable gearing. The actuating dogs 22 of this ratchet mechanism are carried by the universal bar 19. 85

The type on the type levers are maintained in and returned to their normal positions away from the inking ribbon by means of springs 23, one end of each of which is attached to the frame and the other end to the 90 lower arm of a type lever.

When a key lever is depressed for actuating a type lever as above explained, the universal bar will be moved in a direction 100 toward the front of the machine. In thus moving the universal bar, motion is transmitted through the arms 17, links 16 and levers 15 to the paper-feed mechanism and motion will also be transmitted by such forward movement of the universal bar to the dogs 23 of the ratchet mechanism, thus actuating said ratchet mechanism to impart motion for feeding the ribbon. If movement of the arms 9 in a direction toward the 105

rear of the machine be limited, the strokes of the type levers, the paper-feed mechanism and the ribbon feed mechanism will also be limited. It is valuable and important to be able to accurately and synchronously adjust the strokes of these parts of the mechanism and for this purpose the devices now to be explained are employed.

A yoke 24 is disposed behind the arms 9 of the key levers and carries in its horizontal portion, a pad 25 to be engaged by said arms. The lower portions of the depending arms 26 of the yoke 24 are disposed behind a bar 27 fixed in the frame-work 1. This bar is provided with partly spherical projections 28 and the adjacent arms of yoke 24 are made with similarly shaped sockets 29 to receive said spherical projections, thus permitting a slight rocking adjustment of the yoke 24. To effect such adjustment and to retain the yoke in the position in which it may be adjusted, screws 30 are passed freely through holes 31 in the yoke arms above and below the mounting of said arms on the bar 27 and these screws enter threaded holes or sockets 31^a in the bar 27. It is apparent that by unscrewing one of the screws and screwing the other screw in each yoke arm, the yoke will be rocked on its bearing and the pad 25 carried by the horizontal portion of said yoke will be adjusted either in a direction toward or away from the key lever arms 9. The pad 25 carried by the yoke 24 constitutes a stop which limits the forward movement of the key lever arms and hence limits the backward movement of the upper arms of the type levers and regulates the normal space between the type and the platen. Should it be desired to shorten the stroke of the type levers, the yoke 24 will be adjusted, by means of the screws 30, in such manner as to move the pad 25 in a direction toward the key lever arms 9 and to lengthen the stroke of the yoke will be adjusted in the reverse direction.

In view of the fact that the operation of the key and type lever mechanism actuates the universal bar 19 and that both the paper-feeding mechanism and the ribbon-feeding mechanism are actuated by the movements of said universal bar, it will be seen that the adjustments of the yoke 24 as above described will not only adjust the stroke of the type levers, but will also adjust synchronously the strokes of the paper-feed and ribbon-feed mechanisms,—so that with the use of my improvements all of the actuating mechanisms of the machine may be

adjusted simultaneously and in synchronism with each other.

Having fully described my invention, what I claim as new and desire to secure by Letters-Patent, is;

1. In a type-writing machine, the combination with key and type mechanisms, a platen and paper feed mechanism, of means actuated by the key and type lever mechanism for actuating the paper-feed mechanism and means adjustable relatively to said mechanisms for adjusting the strokes of all of said mechanisms simultaneously.

2. In a type-writing machine, the combination with key and type lever mechanism, a platen, paper-feed mechanism, and ribbon-feed mechanism, of means operatively connecting said mechanisms, and adjusting means associated with one of said mechanisms and operative to adjust the strokes of all of said mechanisms simultaneously.

3. In a type-writing machine, the combination with key levers having arms, type levers operatively connected with said arms, and a platen, of a yoke adjacent to and having a part constituting a stop for the key lever arm, and means for effecting a rocking adjustment of said yoke to move the part thereof which constitutes a stop uniformly with respect to all of said key lever arms and thereby vary the stroke of the key levers and the type levers and for securing said yoke in its adjusted position.

4. In a type-writing machine, the combination with writing means, paper-feeding means, and ribbon-feeding means operatively connected with each other, of a fixed bar and a yoke mounted to be rocked on said bar and constituting a stop associated with one of said mechanisms and means above and below the mountings of said yoke on the fixed bar for adjusting the yoke in two directions to adjust the strokes of all of said mechanisms simultaneously.

5. In a type-writing machine, the combination with key and type lever mechanism, a platen, paper feed mechanism and ribbon feed mechanism of means operatively connecting said mechanisms, and means for adjusting the strokes of said mechanisms synchronously.

In testimony whereof, I have signed this specification in the presence of two subscribing witnesses.

WARD S. IRELAND.
